UNITED STATES PATENT OFFICE.

WILLIAM L. CASPER, OF BROOKLYN, NEW YORK, ASSIGNOR TO WESTERN ELECTRIC COMPANY, INCORPORATED, OF NEW YORK, N. Y., A CORPORATION OF NEW YORK.

TRANSMISSION CIRCUITS.

Application filed August 4, 1922. Serial No. 579,593.

This invention relates to transmission circuits, and particularly to such circuits in which amplifying devices are employed.

An object of this invention is to prevent 5 an amplifying device from singing due, for example, to a portion of the output energy, finding its way back into the input circuit of the device.

Another object is to reduce the resonance 10 peak in the transmission characteristic curve of an amplifying device, caused by resonance effects between the capacity existing between the terminals of the amplifying device and external inductance elements.

15 This invention is hereinafter described in detail in connection with an amplifier circuit working into a load which has a falling frequency transmission characteristic. As explained in my Patents Nos. 1,530,648 and 20 1,530,649, issued March 24, 1925, the leakage inductance of an input transformer of an amplifier or a separate series inductance element of suitable value may be made to resonate with capacity effects between the electrodes of the amplifier to give a transmission characteristic rising with frequency. Such a rising characteristic over the transmission band is frequently of importance when the amplifier works into a translating 25 device having a transmission characteristic falling with the frequency. This rising characteristic is frequently obtained by resonating the leakage inductance and the capacity effects at a frequency above the desired transmission range, a suitable filter being employed to suppress frequencies around the resonance frequency, so that the shape and character of the peak does not enter into the transmission characteristic of the repeater system. In the absence of such a filter, 30 however, the transmission at or near the resonance frequency may be so much greater than that over the essential range that the amplifier sings or howls at the resonance frequency—an effect which is, of course, undesirable.

In accordance with this invention, a simple and effective way of reducing this resonance peak to a value comparable to the remainder of the transmission curve is by connecting a condenser across two of the electrodes of the amplifier. This, while lowering the frequency of the resonance peak, has also been found to reduce to a considerable 55 extent the height of the peak and the con-

denser can readily be made of such a value that the transmission at the resonating frequency is of the same order as the transmission for the lower speech frequency, thereby enabling the amplifier to work with high 60 amplification without danger of singing at the higher frequencies.

Referring to the drawings,

Fig. 1 illustrates an amplifier circuit embodying this invention in which the correcting condenser is connected across the grid and cathode electrodes of the amplifier. 65

Fig. 2 is a modification of Fig. 1 in which the correcting condenser is connected across the grid and anode electrodes. 70

Fig. 3 illustrates, by means of curves, the effect of shunting two of the electrodes of an amplifier by a condenser.

Fig. 1 discloses a vacuum tube amplifier 10 connected between an incoming line 11, 11 and an outgoing line 12, 12 for impressing upon the outgoing line in amplified form signals impressed upon the tube from incoming line 11. The control electrode 13 and the cathode 14 of the amplifier are connected to the incoming line 11 by an input transformer 15, while the anode 16 and cathode 14 are connected to the outgoing line 12 by a suitable output transformer 17. The cathode 14 is heated by a battery or 15 other source of voltage 18 and batteries 19 and 20 are employed for maintaining respectively the grid and the anode at suitable potentials with respect to the cathode. 20

As has been explained, it is frequently desirable to have a vacuum tube repeater operating with a transmission characteristic rising with frequency. One way this may be accomplished is to resonate the capacity effects existing between the electrodes of the tube with a small inductance in series with a winding of the input transformer. An actual inductance element separate from the input transformer is not necessary since it has been found that leakage reactance in an input transformer may be adjusted to function the same as a series inductance element. 25 For example, in Fig. 1 the dotted inductances 21 and 22 may represent the effective series inductance caused by leakage reactance in transformer 15. These effective inductances may be made to resonate with the capacity effects between the grid 13 and cathode 14 at a frequency in the upper speech range such as shown by curve 23 of Fig. 3 30 110

wherein the abscissæ represent frequency and the ordinates represent the gain of the amplifier expressed in miles of standard cable.

5. This rising transmission characteristic is particularly useful when the amplifier works into a translating device, such as a loud speaking receiver, the transmission equivalent of which has a characteristic falling with the frequency. The resonance peak of curve 23 however occurs at a frequency which is generally not essential to give quality transmission and may, for example, occur at a frequency slightly above 8000 cycles per second. This resonance peak frequently is of such a magnitude that the amplifier tends to sing or howl due to a portion of the output energy of the resonating frequency being fed back into the input circuit of the tube 10 and re-amplified. This feed back of energy is, of course, objectionable even when the feed back occurs at a frequency above audibility.

In order to overcome this tendency to sing 25 due to the amplification produced near the resonating frequency, this invention provides a condenser 24 connected in shunt to the grid and cathode of the tube. The presence of this condenser lowers the resonating 30 frequency and, at the same time, has been found to give the result that the resonance peak is of a considerably less magnitude. Curve 25 of Fig. 3 illustrates, for example, the transmission characteristic obtained by 35 employing a condenser 24 of such a value that the resonance peak occurs in the neighborhood of 6000 cycles per second. This curve shows that the resonance peak is of a considerably less height and also rapidly 40 falls off for frequencies above the resonating frequency so as to act substantially as a cut-off filter. Due to the presence of condenser 24 and the resulting lowering of the resonance peak, the amplifier 10 can be worked 45 at greater amplification without danger of singing being produced.

It has been found that substantially the same results may be obtained by connecting the correcting condenser between the grid 50 and anode. Fig. 2 illustrates a condenser 27 connected across the grid 28 and anode 29 of a vacuum tube repeater 30. This condenser 27 may be made to resonate with the leakage reactance of the input transformer 55 31 and the capacity effects between the electrodes of tube 30 to give the transmission characteristic illustrated as curve 32 of Fig. 3 whereas the absence of the correcting condenser 37 would give a transmission characteristic similar to curve 23.

As a specific example of the value condenser 24 of Fig. 1 may have, it may be stated that in one case where the effective grid cathode capacity was 100 micromicrofarads and the leakage reactance gave an

equivalent inductance in series with the primary winding of .25 henry, with a transformer having an impedance ratio of 1:16, the condenser 24 had a value 110 micromicrofarads giving a resonance peak at 5500 cycles per second. If an actual inductance element is inserted in series with the primary winding, its value will, of course, be dependent upon the impedance ratio of the transformer and should be multiplied by the 75 impedance ratio to determine the effective inductance resonating with the shunt capacity.

While this invention has been described above in certain specific embodiments, it is to be understood that the invention may possess other different forms without departing in any wise from the spirit of the invention as defined in appended claims.

The invention claimed is:

1. The combination with two transmission lines across one of which an appreciable capacity effect exists, and means for coupling said lines to provide substantially constant transmission between said lines for a wide band of frequencies, said capacity effect tending to cause the upper frequencies of said band to be less efficiently transmitted than the intermediate frequencies thereof, and means tending to resonate with said capacity to substantially equalize the transmission at said intermediate frequencies and said upper frequencies while maintaining the transmission efficiency for said intermediate frequencies substantially unchanged at the value caused by said capacity effect; of a capacity connected across one of said lines and proportioned to lower the frequency at which said first mentioned capacity and means tend to resonate.

2. The combination with means comprising a transformer and a space discharge device, said means having a transmission frequency characteristic showing high transmission efficiency for electrical variations over a wide frequency band, said means including inductance effectively in series with a winding of said transformer, and said device comprising electrodes and an effective input capacity tending to cause the upper frequencies of said band to be less efficiently transmitted than the intermediate frequencies thereof, said effective input capacity resonating with said inductance at such a frequency that the transmission frequency characteristic of said means rises with frequency at and above the upper limit of said band and remains substantially unchanged for said intermediate frequencies at the value caused by said effective input capacity; of a capacity connected across certain of said electrodes and of such a value that the transmission frequency characteristic of said means is lowered at the frequency of said first mentioned resonance.

3. The combination with means comprising a transformer and a space discharge device, said means having a transmission frequency characteristic showing high transmission efficiency for electrical variations over a wide frequency band, said means including inductance effectively in series with a winding of said transformer, and said device including a cathode and a control electrode between which an appreciable capacity effect exists tending to cause the upper frequencies of said band to be less efficiently transmitted than the intermediate frequencies thereof, said capacity resonating with said inductance at such a frequency that the transmission frequency characteristic of said means rises with frequency at and above the upper limit of said band and remains substantially unchanged for said intermediate frequencies at the value caused by said capacity effect; of a capacity connected across said cathode and control electrode and of such a value that the transmission frequency characteristic of said means is lowered at the frequency of said first mentioned resonance and maintained rising with frequency above said band.

4. A transmission circuit comprising an incoming line and an outgoing line, an amplifier for repeating from said incoming line to said outgoing line electrical variations extending over a wide frequency band, said amplifier having electrodes between which an appreciable capacity effect exists, said capacity effect acting to cause the value of the transmission efficiency of said amplifier for intermediate frequencies to be higher than the transmission efficiency for upper frequencies of said band, means resonating with said capacity for substantially equalizing the transmission at said intermediate frequencies and said upper frequencies while the transmission efficiency for said intermediate frequencies remains substantially unchanged at the value caused by said capacity effect, and a capacity connected across two of the electrodes of said amplifier and of such a value that the transmission efficiency of said amplifier is lowered at the frequency of said first mentioned resonance. 50

In witness whereof, I hereunto subscribe my name this 2nd day of August, A. D. 1922.

WILLIAM L. CASPER.
